UNITED STATES PATENT OFFICE.

JOHN M. FLANNERY, OF DETROIT, MICHIGAN, AND FRANK C. DETTELBACH, OF CLEVELAND, OHIO, ASSIGNEES, BY MESNE ASSIGNMENTS, TO THE EAGLE CARBURETER COMPANY, OF CLEVELAND, OHIO, A CORPORATION OF OHIO.

CARBURETOR.

1,419,035.

Specification of Letters Patent. Patented June 6, 1922.

Application filed March 10, 1919. Serial No. 281,766.

To all whom it may concern:

Be it known that we, (1) JOHN M. FLANNERY and (2) FRANK C. DETTELBACH, citizens of the United States, residing at (1) 5 Detroit, (2) Cleveland, in the county of (1) Wayne, (2) Cuyahoga and State of (1) Michigan, (2) Ohio, have invented a certain new and useful Improvement in Carburetors, of which the following is a full, clear, and 10 exact description, reference being had to the accompanying drawings.

This invention relates to carburetors of the type employed for the production of an explosive mixture of air and hydro-carbon 15 for the operation of an internal combustion engine as in automobiles, boats, airplanes, tractors, and stationary power plants. For illustrative purposes we have shown our improved carburetor in connection with an automobile engine owing to the particularly 20 severe requirements flowing from the wide speed-range demanded and the necessity of large torque at low speeds. It will be understood however that neither in this nor 25 in other details are we limited to the features of our drawing or specific description since the same is intended to be only interpretative of our generic idea rather than exhaustive of its specific application.

30 The objects of our invention are the provision of a carburetor which shall afford a rich mixture at low speed graduating uniformly to a comparatively lean mixture at high speed, whereby maximum torque is obtained under all conditions and with a minimum fuel consumption; the provision of a carburetor which shall be proof against flooding or choking; the provision of a carburetor of extremely simple construction; 35 the provision of a carburetor which shall in some cases at least permit vacuum tanks or the like separate feeding devices to be dispensed with; while further objects and advantages of our invention will become apparent as the description proceeds.

In the drawings accompanying and forming a part of this application, we have, for purposes of illustration but not of limitation, shown the construction and mode of 40 operation of one practical embodiment of our inventive idea. In these drawings Fig.

1 represents an automobile engine equipped with our improved carburetor; Fig. 2 is a vertical sectional view through the carburetor showing the throttle closed; Fig. 3 is 55 a sectional view on the line 3—3 of Fig. 2; Fig. 4 is a view similar to Fig. 2 but showing the throttle in open position; Fig. 5 is a perspective view of the carburetor, the mixing chamber having been removed; and 60 Fig. 6 is an enlarged detail sectional view of the nozzle.

Describing by reference characters the parts shown in the drawings, 1 represents the float chamber of our improved carburetor having projecting from its side the annular bracket 2 which is traversed by a horizontal web 3. The top of the bracket 2 is formed with a seat 4 for the reception of the cylindrical mixing chamber 5, while the bottom of the same is formed with a seat 6 adapted for the reception of the inlet elbow 7, the parts 5 and 7 being secured in place by screws (not shown) engaging the ears 8, 8 of the bracket. Carried by the web 3 70 is the fuel nozzle 10 which rises vertically into the axis of the mixing chamber and is preferably formed at its upper end with a laterally enlarged head terminating in a flat top wall 11 defined by an annular slanting 75 portion 12. The top 11 is also surmounted by an upright cylindrical flange 13 forming a cup.

This nozzle is formed with a vertical axial fluid-passage 15 leading from the bottom of said cup to the interior of the web 3 where it joins the horizontal passage 16 leading to the fluid chamber; and also with a plurality of branch passageways 17, 17 which open through the slanting portion 12 90 and join the main passage 15. Formed in the bottom surface of the web 3 is a chamber 18, wholly disconnected from the fuel ducts, but communicating with the bottom of the cup 13 by means of a plurality of narrow 95 ducts 19 which are so arranged as to avoid all the fuel passageways. The chamber 18 communicates freely with the outer air by means of a pipe 20 which passes through the side of the elbow 7, and the throttle 21 is 100 located in this elbow.

Mounted in the chamber 5 is a slidable

venturi 25, formed intermediate of its length with an inclined seating portion 26 adapted when in depressed position to engage the slanting portion 12 outside of its ports 17, 5 and having above and below said seat the outwardly flaring portions 27 and 28 respectively. The top of the chamber 5 is shown as flanged at 29 for attachment to the engine manifold 30 in the usual manner, 10 and is also placed in open communication with the interior of the float chamber 21 by any suitable means such as the pipe 31, the float chamber being otherwise hermetically sealed so that no air can enter the same. 15 From the float chamber a fuel supply pipe 33 leads to the fuel tank 34 which may be disposed a nearer or greater distance as will hereafter be explained, and inside the float chamber is a float 35 which cooperates with a 20 valve rod 36 to close the valve seat 37 with which the pipe 33 communicates.

The connection between the float and valve rod may be of any suitable or desired type but we have found the construction shown 25 herein particularly advantageous, that is to say: the upper end of the rod 36 is threaded for the reception of an adjustable sleeve 40 which is provided at its lower end with a groove 41 receiving the inner ends of levers 30 42 whose outer ends engage the float. The rod 36 also carries a jam nut 43 which locks the sleeve in position while permitting adjustment thereof to raise or lower the fuel level. The sleeve and rod project upwardly 35 through a hole in the top of the float chamber but are housed in a cap 45 which is hermetically screwed thereon.

The operation of the device is as follows: 40 The float is adjusted so as normally to cause the rod 36 to close the fuel inlet when the liquid level reaches the line *a* in Fig. 2. We will assume however that the float chamber is drained of liquid and that the tank is below the level thereof, the throttle 31 being 45 closed. Upon the cranking of the engine the first effect is to create a very high vacuum in the carbureting chamber and manifold, frequently equivalent to 20 inches of mercury or 9 pounds per square inch below atmospheric. This vacuum is transmitted to the 50 float chamber by the pipe 31 and serves immediately to elevate a supply of fuel therein from the tank 34; and experience shows that not only does the float chamber become 55 filled to the level *a*, but also to a higher level *b* owing to the fact that the upward pressure of the fuel against the valve rod 36 overcomes the seating tendency produced by the float excepting upon a deeper submergence. This tendency is decreased by decreasing 60 the size of the valve-seat aperture and by increasing the ratio of the levers 42. This action may be and sometimes is available as affording a measure of speed-compensation 65 as will hereafter be explained, but need not

be so used. In any case, however, it is imperative that the maximum level be lower than any of the nozzle ports.

The suction in the manifold sets up a rapid rush of air through the pipe 20 and 70 ducts 19, which air, owing to the constrictive effect of the cup 13, aspirates fuel through the vertical duct 15, and by a proper proportioning of those ducts produces a mixture of exactly the right composition for idling 75 purposes. So long as the throttle 21 remains closed the sliding venturi remains seated upon the nozzle top and the fuel jets 17 remain wholly inactive. If now the throttle 21 be opened, the inrush of air will lift 80 the venturi to or towards the position shown in Fig. 4 (depending upon the amount of throttle opening) and the rush of air past the ports 17 will aspirate fuel therethrough with the production of an explosive mixture 85 at this point. The richness of this mixture will decrease with the opening of the throttle for three reasons: First, because with the increasing elevation of the venturi the distance between the nozzle and the portion 28 90 becomes gradually wider thereby decreasing the aspirating effect upon the ducts; second, because with the decrease of manifold-suction produced by the throttle opening the aspiration of air through the passageways 95 19 falls off or ceases; and third, because with the decrease in suction the liquid level in the float chamber falls from *b* toward *a* and thus decreases the flow tendency. If the throttle be opened gradually these changes 100 in mixture are substantially uniform; but if the throttle be opened suddenly, the excessive level in the float chamber tends to effect a priming action, giving a richer mixture 105 for a few seconds and thus facilitating the acceleration of the motor.

As previously stated this variation in liquid level can be utilized as a part of the compensation if desired or it can be largely ignored. By making the needle valve small 110 and the lever ratio high, the liquid level can be kept within fairly narrow bounds, and this indeed is desirable in case the fuel is to be elevated from a tank 34 at any great depth or long distance. But in case the fuel reservoir is close at hand, the lever ratio and valve seat opening can be adjusted so as to afford a large variation in liquid level and hence of automatic compensation arising 115 from this source.

It will be understood that we do not confine ourselves to the elevation of fuel from a tank placed beneath the carburetor, since it can equally well be fed from above; we do not restrict ourselves to the omission of a 125 vacuum tank or other feeding device; the float valve and its adjuncts can take a great number of forms; the number of fuel ducts and air ducts in the nozzle can be varied; other means than unassisted air pressure can 130

be employed for moving the venturi; and numerous other changes of detail construction and arrangement can be made within the scope of our invention which is limited 5 only by the prior art.

Having thus described our invention, what we claim is:—

10 In a carburetor, in combination, an upright mixing chamber, a fuel nozzle therein having an enlargement, a slidable venturi in said chamber having a constricted portion adapted either to seat upon the enlargement of said nozzle and close the passage sur-

rounding the same or to be elevated thereabove producing a variable passage, said 15 nozzle being formed with a second air passage independent of the first passage, and with independent fuel ducts cooperating with the respective passages and means for controlling the flow of air through said first 20 passage.

In testimony whereof, we hereunto affix our signatures.

JOHN M. FLANNERY.
FRANK C. DETTELBACH.
